In Germany December 6, 1950

15 Claims. (Cl. 51—48)

1

Our present invention relates to a centerless grinding device.

The grinding device of our present invention is especially suited for centerless grinding of rollers and pairs of rollers as they are employed in spinning frames.

One of the objects of our present invention is to provide a device for grinding roller-shaped bodies of simple construction comprising but inexpensive parts.

Another object of our present invention is to provide a grinding device for roller-shaped bodies which insures that said bodies receive true right circular cylindrical surfaces.

A further object of our invention is to arrange the roller-shaped bodies to be ground in such a manner that they automatically adjust themselves with their axes parallel to the axis of the driving means.

With the above objects in view, a preferred embodiment of our present invention mainly consists of a frame, a driving roller substantially horizontally arranged and adapted to drive the roller-shaped bodies when the latter are provided on top of the driving rollers with their axes being substantially parallel, driving means for driving said driving rollers, a rotating grinding disk adapted to be reciprocated along the surface of the roller-shaped bodies in a direction parallel to the axis of the driving roller, a bracket of suitable shape, a ball-cup mounted on said frame, said bracket having at least one bearing half on one end adapted to partly embrace the axle or supporting pin or pins of said roller-shaped bodies and having a ball at its other end adapted to be received in that ball-cup, a weighting means adapted to press the roller-shaped bodies on said driving roller.

The novel features which are considered as characteristic for the invention are set forth in particular in the appended claims. The invention itself, however, both to its construction and its method of operation, together with additional objects and advantages thereof, will be best understood from the following description of specific embodiments when read in connection with the accompanying drawings, in which:

Fig. 1 is an elevational view of one embodiment of our present invention;

Fig. 2 is a top view of the device according to Fig. 1;

Fig. 3 is an elevational view of a second embodiment of our present invention;

Fig. 4 is a top view of the device according to Fig. 3;

2

Fig. 5 is a sectional view along line 6—6 of Fig. 6 showing a third embodiment of our present invention;

Fig. 6 is a top view of a third embodiment of our present invention;

Fig. 7 is an elevational view of a fourth embodiment of our present invention with a hand-operated adjusting device;

Fig. 8 is a top view of the device according to Fig. 7;

Fig. 9 is a sectional view of an adjusting device operated by a pressure means.

In Figs. 1 and 2 a driving roller 1 is rotated about its horizontal axis in the direction of the arrow A, the driving and supporting means being not shown in the drawing. A roller-shaped body 2, which is to be ground on the device according to our invention, is supported by the aforementioned driving roller and arranged with its axis parallel to the axis of said roller 1, as this may be seen in Fig. 2. Upon rotation of the driving roller 1 in the direction of arrow A the roller-shaped body 2 is rotated in a direction as indicated by the arrow B. The roller-shaped body 2 is rotatably mounted on an axle 6, e. g., by means of ball bearings 7, however, any other type of bearing is also suitable. The two projecting end-portions 16 of the axle 6 are halfway embraced from above by two half-shells 8, fastened to the end of a fork 9, the latter being part of a guiding bracket 5, 9. As may be seen from Fig. 1 the fork 9 is arranged substantially in a horizontal plane with the end-portions 91 being bent downwardly at right angles and fastened to the two half-shells 8 as mentioned before. The arrangement of the fork will of course be changed to some extent in accordance with the diameter of the roller 2 as the latter is ground off on the device. To the center 92 of fork 9 an arm 5 is secured, whose end-portion 93 is bent downwardly at right angles and carries a ball 4 at the end of this bent-off portion, said ball being supported in a ball-cup 11. The ball-cup is mounted on a supporting rod 121 fastened to a stationary part of the frame 17 of the device.

A weight 15 is by means of a rope 19 suspended from an eye 51 provided on arm 5 of the grinding bracket 5, 9, said weight producing the pressure necessary for properly driving the roller 2 by means of driving roller 1. The grinding wheel, whose driving and supporting arrangement is not shown in the drawing, is denoted by 3 and rotates about its axle 18.

55 Supporting ball 4 in the ball-cup 11 allows the

grinding bracket 5, 9 to swing parallel to the plane determined by the center of ball 4 and the axis of the roller-shaped body 2 and simultaneously allows body 2 to move in such a manner that its axis remains parallel to the position shown in Figs. 1 and 2. Thus the body 2 will always adjust itself with its axis parallel to the axis of the driving roller 1, provided of course that this roller 1 has a circular cylindrical surface rotating about its axis.

The arrangement according to Figs. 1 and 2 may be equipped with a hydraulic device known per se, which allows of advancing either the driving roller 1 together with body 2, towards the grinding disk 3 or of advancing the grinding disk 3 towards the body 2. This device may also be employed to automatically reciprocate the body 2 or the grinding disk 3 respectively in axial direction in a conventional manner for carrying out the grinding process. However, any other suitable device for reciprocating the grinding disk 3 and advancing body 2 or disk 3 towards each other may be employed without departing in any way from the device according to our invention. For example, as is shown in Fig. 2, driving roll 1 is mounted for rotation on bearings 50 of the apparatus and has fixedly mounted thereon a pulley 51 adapted to be driven by a belt from any suitable source of power. The shaft 18, which carries the grinding wheel 3, is formed with splines 52 mating with the internally splined pulley 53 which is turned by a belt from any suitable source of power. The shaft 18 is mounted for rotating in the bearings 54 of the apparatus and has fixedly connected thereto a ring 55 engaged by the shifting fork 56 which is pivotally mounted for reciprocating turning movement on the support 57 of the apparatus so that the grinding wheel 3 may be rotated about its axis by turning of pulley 53 and reciprocated in the direction of its axis by movement of shifting fork 56.

Figs. 3 and 4 show another embodiment of our invention where the fork 309 carrying the two half-shells 8 is bent in such a manner that it extends underneath the grinding disk 3 arranged in this case between body 2 and a ball-joint. At the end of an arm 305 fastened to fork 309 at 306, a ball 4 is provided, said ball being supported in a ball-cup 11 similar to the arrangement according to Figs. 1 and 2. The necessary pressure between body 2 and driving roller 1 is produced in this embodiment by a spring 308 attached at one end to an eye 307 of arm 305 and at its other end to a frame portion 310 of the device.

Figs. 5 and 6 show an arrangement for grinding pairs of grinding rollers 402. In Fig. 6 two pairs of grinding rollers 402 and two grinding wheels 403 are arranged with their respective axes aligned. The pairs of grinding rollers 402 are connected by a common axle 406 with the half-shells 408 being arranged on the upper half of that part of axle 406 provided between the grinding rollers 402. Since the grinding rollers 402 are arranged in pairs with an interconnecting axle 406, it is now possible to provide only one grinding bracket 405 for each pair of grinding rollers 402, said bracket being bent in proper form so as to clear the grinding wheel 403. The downwardly bent end-portion 407 of the bracket 405 is provided with a ball 4 supported by a ball-cup 11 similar to the arrangement shown in Figs. 1 and 2 or Figs. 3 and 4 respectively.

In Figs. 7 and 8 a hand-operated device for advancing the roller-shaped body 2 is illustrated.

Parts identical with prior figures are designated by the same denotations. The grinding bracket 605 shows a similar form as in Figs. 3 and 4, except that the end-portion 634 is not provided with a ball-joint, but is straight-shaped, said end-portion 634 carrying a clamping-sleeve 616 slidably arranged on this portion, which may be fixed in position by a wing-screw 617. On the lower side of clamping-sleeve 616 a supporting rod 615 is fastened which carries a ball 4 at its end-portion, said ball being supported in a ball-cup 11. The latter is arranged on a threaded sleeve 614 adapted to be moved back and forth on a screw 613 suitably supported at one end in a frame-portion 635 and on the other end in a box 635.

By turning the threaded screw 613, the threaded sleeve together with ball-joint 411, clamping-sleeve 616 and thus bracket 605 with body 2, may be moved back and forth. Another position of the ball-joint 411 is indicated in dot-dash-lines corresponding to a ground-off roller-shaped body 2, illustrated in dot-dash-lines. Rotation of screw 613 is achieved by turning a crank 619, the motion being transmitted through two shafts 611 and two pairs of bevel gears 612 with one bevel gear being fastened to screw 613.

Advancing of the roller-shaped body 2 may also be accomplished by means of a pressure medium as illustrated in Fig. 9 by way of example. In this embodiment the ball-cup 11 is fastened to a sliding-block 620 slidably arranged in a guiding tube 622, which is supported at one end in a frame-portion 633 and at the other on a ring-shaped flange of a cover 636. The latter is attached, by means of screws 627, to a cylinder 625 in which a piston 624 fitted with a piston rod 621 may reciprocate. The piston rod 621 is rigidly attached to sliding block 620 so that the motion of piston 624 may be transmitted to the sliding block 620 and thus through ball-joint 411, clamping-sleeve 616, bracket 605 to the roller-shaped body 2 not shown in this figure. From a valve 630 with inlet pipe 632 for admitting a pressure medium and with an outlet 631 for allowing the pressure medium to escape, two pipes 628 and 629 lead to the left and right chambers of the cylinder 625 respectively, said chambers being separated by piston 624. By turning lever 637 of the valve 630 to the left or right, the piston 624 will be moved in left or right direction as desired. In the center position of lever 637 the piston will remain at rest.

When a piece is ground off by a slight amount, it may suffice to only advance the roller-shaped body as this is diagrammatically shown in the arrangement in Figs. 7 to 9. Otherwise it may be advantageous to also advance the grinding wheel.

The roller-shaped bodies are properly ground off in a right circular cylindrical shape when the surface of the driving roller has the accurate form of a right circular cylinder and runs true. The best grinding results are achieved when the center of ball 4, and the axis of the grinding disk, and the roller-shaped body are arranged substantially in one plane as this is shown, e. g., in Fig. 1 or Fig. 7, when the dot-dash-lines are considered in the latter case.

The forces acting on the guiding bracket producing the necessary pressure between driving roller and the roller-shaped body must be such that the automatic adjustment of the roller-shaped body to a position with its axis parallel to that of the driving roller is in no way impeded. It is therefore best to employ a weight freely

suspended from the guiding bracket and to arrange the axis of the driving roller horizontally so as to prevent the production of a component force of the weight in axial direction. The weight may of course be replaced by other force generating means, e. g., a spring, as indicated in some of the embodiments of our invention.

While we have illustrated and described our invention in various embodiments, we do not intend to be limited to the details shown, since various modifications and structural changes may be made without departing in any way from the spirit of our invention.

Without further analysis, the foregoing will so fully reveal the gist of our invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What we claim as new and desire to secure by Letters Patent is:

1. Centerless grinding device for grinding roller-shaped bodies having axles or axially arranged bearing pins protruding from said bodies comprising in combination a frame, a driving roller substantially horizontally arranged and adapted to drive said roller-shaped bodies when they are provided on top of said driving roller with their axes substantially parallel, driving means for driving said roller, a rotating grinding disk adapted to be reciprocated along the surface of the roller-shaped bodies in a direction parallel to the axis of the driving roller, a bracket of suitable shape, a ball-cup mounted on the frame, said bracket having at least one bearing half on one end adapted to partly embrace the axle or bearing pin or pins of said roller-shaped bodies and having a ball at its other end adapted to be received in said ball-cup, a weighting means adapted to press the roller-shaped bodies on the driving roller.

2. Centerless grinding apparatus, comprising in combination, a driving roller mounted, on the apparatus, for rotation about its axis and being adapted to rotate the work to be ground by frictional contact therewith; a grinding wheel mounted on the apparatus and having an axis of rotation located to one side of and at a different elevation than the axis of said driving roller; elongated work holding means for holding the work on said driving roller and against said grinding wheel, said work holding means having one end located in vertical alignment with said driving roller and adjacent to said grinding wheel and an opposite end distant from said one end; bearing means fixedly mounted on said one end of said work holding means to engage the work to be ground while permitting the same to be rotated by said driving roller; ball and socket means fixedly connected to said opposite end of said work holding means to support the latter for universal movement; and pressure means operatively connected to said work holding means to urge said one end thereof toward said driving roller so as to press the work against said driving roller to be rotated thereby.

3. Centerless grinding apparatus, comprising in combination, a driving roller horizontally mounted, on the apparatus, for rotation about its

axis and being adapted to rotate the work to be ground by frictional contact therewith; a grinding wheel mounted on the apparatus and having an axis of rotation parallel to, located to one side of and at a different elevation than said driving roller; elongated work holding means for holding the work on said driving roller and against said grinding wheel, said work holding means having one end located in vertical alignment with said driving roller and adjacent to said grinding wheel and an opposite end distant from said one end; bearing means fixedly mounted on said one end of said work holding means to engage the work to be ground while permitting the same to be rotated by said driving roller; ball and socket means fixedly connected to said opposite end of said work holding means to support the latter for universal movement, said ball and socket means being located in a horizontal plane which includes said axis of rotation of said grinding wheel; and pressure means operatively connected to said work holding means to urge said one end thereof toward said driving roller so as to press the work against said driving roller to be rotated thereby.

4. Centerless grinding apparatus, comprising in combination, a driving roller horizontally mounted, on the apparatus, for rotation about its axis and being adapted to rotate the work to be ground by frictional contact therewith; a grinding wheel mounted on the apparatus and having an axis of rotation parallel to, located to one side of and at a different elevation than said driving roller; elongated work holding means for holding the work on said driving roller and against said grinding wheel, said work holding means having one end located in vertical alignment with said driving roller and adjacent to said grinding wheel and an opposite end distant from said one end; bearing means fixedly mounted on said one end of said work holding means to engage the work to be ground while permitting the same to be rotated by said driving roller; ball and socket means fixedly connected to said opposite end of said work holding means to support the latter for universal movement, said ball and socket means being located in a horizontal plane which includes said axis of rotation of said grinding wheel; and pressure means operatively connected to said work holding means to urge said one end thereof toward said driving roller so as to press the work against said driving roller to be rotated thereby.

5. Centerless grinding apparatus, comprising in combination, a driving roller horizontally mounted, on the apparatus, for rotation about its axis and being adapted to rotate the work to be ground by frictional contact therewith; a grinding wheel mounted on the apparatus and having an axis of rotation parallel to, located to one side of and above the axis of said driving roller; elongated work holding means for holding the work on said driving roller and against said grinding wheel, said work holding means having one end located over said driving roller and adjacent to said grinding wheel and an opposite end distant from said one end; bearing means fixedly mounted on said one end of said work holding means to engage the work to be ground while permitting the same to be rotated by said driving roller; ball and socket means fixedly connected to said opposite end of said work holding means to support the latter for universal movement, said ball and socket means being located in a horizontal plane which includes said

axis of rotation of said grinding wheel; and pressure means operatively connected to said work holding means to urge said one end thereof toward said driving roller so as to press the work against said driving roller to be rotated thereby.

6. Centerless grinding apparatus as defined in claim 5 and wherein said pressure means is in the form of a weight suspended from said work holding means.

7. Centerless grinding apparatus as defined in claim 5 and wherein said pressure means is in the form of a coil spring connected to said work holding means and extending downwardly therefrom.

8. Centerless grinding apparatus as defined in claim 5 and wherein said one end of said work holding means is located between said opposite end thereof and said grinding wheel.

9. Centerless grinding apparatus as defined in claim 5 and wherein said grinding wheel is located between said ends of said work holding means.

10. Centerless grinding apparatus, comprising in combination, a driving roller horizontally mounted, on the apparatus, for rotation about its axis and being adapted to rotate the work to be ground by frictional contact therewith; a grinding wheel mounted on the apparatus and having an axis of rotation parallel to, located to one side of and above the axis of said driving roller; elongated work holding means for holding the work on said driving roller and against said grinding wheel, said work holding means having one end located over said driving roller and adjacent to said grinding wheel and an opposite end distant from said one end; bearing means fixedly mounted on said one end of said work holding means to engage the work to be ground while permitting the same to be rotated by said driving roller; ball and socket means fixedly connected to said opposite end of said work holding means to support the latter for universal movement, said ball and socket means being located in a horizontal plane which includes said axis of rotation of said grinding wheel; pressure means operatively connected to said work holding means to urge said one end thereof toward said driving roller so as to press the work against said driving roller to be rotated thereby; and moving means operatively connected to said work holding means for moving said one end thereof toward said grinding wheel.

11. Centerless grinding apparatus, comprising in combination, a driving roller horizontally mounted, on the apparatus, for rotation about its axis and being adapted to rotate the work to be ground by frictional contact therewith; a grinding wheel mounted on the apparatus and having an axis of rotation parallel to, located to one side of and above the axis of said driving roller; elongated work holding means for holding the work on said driving roller and against said grinding wheel, said work holding means having one end located over said driving roller and adjacent to said grinding wheel and an opposite end distant from said one end; bearing means fixedly mounted on said one end of said work holding means to engage the work to be ground while permitting the same to be rotated by said driving roller; ball and socket means fixedly connected to said opposite end of said work holding means to support the latter for universal movement, said ball and socket means being located in a horizontal plane which includes said axis of rotation of said grinding wheel; pressure means opera-

tively connected to said work holding means to urge said one end thereof toward said driving roller so as to press the work against said driving roller to be rotated thereby; and screw means operatively connected to said work holding means for moving said one end thereof toward said grinding wheel.

12. Centerless grinding apparatus, comprising in combination, a driving roller horizontally mounted, on the apparatus, for rotation about its axis and being adapted to rotate the work to be ground by frictional contact therewith; a grinding wheel mounted on the apparatus and having an axis of rotation parallel to, located to one side of and above the axis of said driving roller; elongated work holding means for holding the work on said driving roller and against said grinding wheel, said work holding means having one end located over said driving roller and adjacent to said grinding wheel and an opposite end distant from said one end; bearing means fixedly mounted on said one end of said work holding means to engage the work to be ground while permitting the same to be rotated by said driving roller; ball and socket means fixedly connected to said opposite end of said work holding means to support the latter for universal movement, said ball and socket means being located in a horizontal plane which includes said axis of rotation of said grinding wheel; pressure means operatively connected to said work holding means to urge said one end thereof toward said driving roller so as to press the work against said driving roller to be rotated thereby; and hydraulic means operatively connected to said work holding means for moving said one end thereof toward said grinding wheel.

13. Work holding apparatus for holding work to be ground in a centerless grinder, comprising in combination, an elongated member having a central portion formed from two legs, one of said legs being perpendicular to the other of said legs and having an end fixed to said other leg at a central portion of the latter so that said central portion of said member is T-shaped, a pair of additional legs respectively extending from the extremities of said other leg in a direction away from said one leg, each of said pair of additional legs having an outer free bent end portion substantially forming a right angle with the remainder of said additional leg, and said one leg having a free end portion located at the opposite end thereof from said other leg and being bent from the remainder of said one leg, said free end portion of said one leg being parallel to said free end portions of said additional legs; a pair of arcuate bearing plates respectively fixed to said free end portions of said pair of additional legs and each having a bearing surface in the form of a half cylinder; and a ball, of a ball and socket joint, fixedly connected to said free end portion of said one leg.

14. Work holding apparatus for holding work to be ground in a centerless grinder and comprising in combination, a U-shaped portion having a pair of opposite first legs and a cross leg extending from one end of one of said first legs to one end of the other of said first legs; a pair of second legs respectively extending in the same direction from an end of each of said first legs opposite to said one end thereof, said second legs being parallel to each other, perpendicular to said first legs, and each having an end located distant from said first legs; a pair of third legs respectively extending from said ends of said second

legs, being perpendicular thereto and parallel to each other and said first legs, each of said third legs having an end located distant from said second legs; a pair of fourth legs respectively extending from said third legs, being perpendicular thereto and parallel to each other and said second legs, each of said fourth legs having a free end located distant from said third legs; a pair of arcuate bearing plates respectively fixed to said free ends of said fourth legs and each having a bearing surface in the form of a half cylinder; an elongated arm connected at one end thereof to a central part of said cross leg and being perpendicular thereto, said arm being parallel to said third legs and having an end located distant from said cross leg; a fifth leg extending from said end of said arm and being perpendicular thereto, said fifth leg being parallel to said second legs and extending in the same direction as the latter, and said fifth leg having an end located distant from said arm; a sixth leg extending from said end of said fifth leg, being perpendicular thereto and parallel to said arm, said sixth leg having an end located distant from said fifth leg; a seventh leg extending from said end of said sixth leg, being perpendicular thereto and parallel to said fifth leg, said seventh leg having a free end; and a ball, of a ball and socket joint, fixed to said free end of said seventh leg.

15. Work holding apparatus for holding work in a centerless grinder and comprising in combination, a pair of opposite spaced arms substantially located in a straight line and each having

an inner end and an outer end, said inner ends of said arms being located nearer to each other than said outer ends thereof; a substantially U-shaped member interconnecting said arms, said U-shaped member having a pair of opposite legs perpendicular to said arms and each having an end connected to one of said inner ends of said arms; an arcuate bearing plate fixedly connected to one of said arms adjacent a central part thereof, said bearing plate having a bearing surface in the form of a half cylinder; and a ball, of a ball and socket joint, fixed to said outer end of the other of said arms.

WILHELM STAHLCKER.
